(57) **CLAIM**

The ornamental design for a hand guard, as shown and described.

DESCRIPTION

FIG. 1 is a front elevation view of the hand guard.
FIG. 2 is a rear elevation view of the hand guard.
FIG. 3 is a left/top/front perspective view of the hand guard.
FIG. 4 is a right elevation view of the hand guard.
FIG. 5 is a left elevation view of the hand guard.
FIG. 6 is a top plan view of the hand guard.
FIG. 7 is a bottom plan view of the hand guard.
FIG. 8 is a right/top/rear perspective view of the hand guard.
FIG. 9 is a right/bottom/rear perspective view of the hand guard.
FIG. 10 is a right/bottom/front perspective view of the hand guard.
FIG. 11 is a right/top/front perspective view of the hand guard.
FIG. 12 is a left/bottom/front perspective view of the hand guard.
FIG. 13 is a left/bottom/rear perspective view of the hand guard; and,
FIG. 14 is a left/top/rear perspective view of the hand guard. The broken line showing of portions of the hand guard for a firearm in all figures is included for the purpose of illustrating environment and forms no part of the claimed design.
